(57) **CLAIM**

The ornamental design for a phototherapy hat as shown and described.

DESCRIPTION

FIG. 1 is a perspective view of a phototherapy hat showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and

FIG. 9 is an enlarged view of the phototherapy hat shown within the area designated as 9 in FIG. 1; and,

FIG. 10 is an enlarged view of the phototherapy hat shown within the area designated as 10 in FIG. 8.

The broken lines in the drawings are for the purpose of illustrating portions of the phototherapy hat that form no part of the claimed design. The dot-dashed broken lines in FIGS. 9-10 show the boundary of the enlarged view and forms no part of the claimed design.
